R. AVERSA

SLIDING AND SWINGING WINDOW SASH BALANCE

Filed Dec. 16, 1927

INVENTOR
Raffaele Aversa
BY *Solomon H. Blackford*
ATTORNEY

UNITED STATES PATENT OFFICE.

RAFFAELE AVERSA, OF NEW YORK, N. Y.

SLIDING AND SWINGING WINDOW-SASH BALANCE.

Application filed December 16, 1927. Serial No. 240,479.

This invention relates to a new and useful device in the nature of a slidable and extensible window for houses, buildings and the like.

5 The object of the invention is to provide a slidable and extensible window of novel construction and arrangement of parts herein-after more fully described, claimed and illustrated in the accompanying drawing.

10 Fig. 1 is a top plan view of my improved slidable and extensible window.

Fig. 2 is a front, inside elevational view thereof.

15 Fig. 3 is a vertical sectional view taken on the line 3—3 of Fig. 2.

Fig. 4 is an enlarged transverse sectional view taken on the line 4—4 of Fig. 2.

Fig. 5 is a sectional view taken on the line 5—5 of Fig. 1.

20 Fig. 6 is a sectional view taken on the line 6—6 of Fig. 1.

Fig. 7 is a fragmentary end elevational view of Fig. 6 partly shown in section and constructed according to modified form.

25 Fig. 8 is a plan view, taken on the line 8—8 of Fig. 7.

As here embodied my improved slidable and extensible window comprises an upper and lower window frame 10 and 11, of rectangular frame construction having panes of glass 12 and 13, respectively, mounted therein and secured thereto preferably by strips 14, 15, 16 and 17, respectively attached to and extended inwardly from the said

30 frame. The window frames 10 and 11 are hinged as at 18 and 19, in the usual manner, to the supports 20 and 21, respectively, slidably mounted vertically in suitable grooves formed in one side of the window casing 22.

40 The supports 20 and 21, are provided with rear inwardly extended elements 23 and 24, respectively, adapted to receive the adjacent portion of the frames 10 and 11, respectively, when the said frames are in a closed position, so as to provide a storm proof joint. The opposite supports 20' and 21' are slidably mounted in the opposite side of the said window casing 23, and are provided with similarly formed elements 23' and 24', adapted

45 to receive the adjacent portions of the said frames 10 and 11 for the purpose as above set forth.

50 Catches 25 and 26 are slidably mounted in the plate members 27 and 28, respectively, secured to the sides of the frames 10 and 11,

respectively, opposite the hinges 18 and 19, and are adapted to slidably engage in openings formed in the adjacent side of the casing 23, as a means of holding the said frames in a closed position. The above described 60 construction is such as will permit the frames 10 and 11 to be vertically raised or lowered, or slidably positioned vertically as may be desired, and which will permit the said upper and lower frames 10 and 11 to be hinged inwardly as designated by the reference numerals 29 and 30 respectively. It is understood that the said lower frame 11 is comparatively wider than the upper frame 10, so as to allow the said lower frame to be 70 hinged inwardly, when positioned at the rear of the lower frame 11, as clearly shown in Fig. 4.

Vertical strips 31 and 32 are secured to and extended inwardly from the sides of the 75 said casing 22, and are positioned intermediate the said supports 20, 21 and 20', 21', respectively, co-acting with the grooves formed in the sides of the casing 22, adapted to receive the said supports, as a means of 80 permitting the said supports to be easily slidably mounted in the said casing. The threaded members 33 and 34, thumb screws, set screws, or the like, are threadedly mounted in the casing 22, and are adapted to 85 engage the supports 20, 20', 21 and 21', respectively, as a means of holding the said frames 10 and 11 in any desired position.

Flexible members 35 and 36, 37 and 38, are secured intermediate to the supports 20', 20, 90 21' and 21, respectively, and are extended upwardly therefrom and are extended over the pulleys 39, 40, 41 and 42 respectively, and secured thereto. Grooves 43 are formed in the above mentioned supports adapted to freely receive the said flexible members. The pulleys 39, 40, 41 and 42 are rotatively mounted on the shafts 43 and 44, respectively carried in the brackets 45, 46, 47 and 48 secured to and extended upwardly from the top portion 100 of the said casing 22. Coil springs 49 co-axial on the shafts 43 and 44, are secured thereto and to the pulleys 39, 40, 41 and 42. The collars 50 and 51 are secured to the shafts 43 and 44 and positioned adjacent to the pulleys 39, 40, 41 and 42 and to the springs 49 as a means of holding the said pulleys and spring in position on the said shafts 43 and 44.

105 The above described construction is such as will permit the said springs 49 to assist in 110

closing the frame 10 and opening the frame 11. It is obvious that the lowering of the said frames 10 and 11 will wind or tension the said springs 49 for the purpose as above set forth.

In Figs. 7 and 8 of the accompanying drawing, I have shown a cylindrical member 52 eccentrically mounted on the pin 53 carried in the lug elements 54 and 55 of the bracket 56 secured to the top portion of the casing 22. The counterweight 57 is slidably mounted on the extended arm element 58 of the cylindrical member 52, and is held in any desired position thereon by means of the threaded member 59, a set screw or the like threadedly mounted in the counter-weight 57 and adapted to engage the arm element 58. The above described construction is such as will permit the cylindrical member 52 to be held in engagement with the pulleys 39, 40, 41 and 42, as a means of partially nullifying the action of the said springs 49 as a means of providing a smooth action mechanism. It is obvious that the counter-weight 57 may be positioned on the arm element 58 so as to secure the desired engagement of the said cylindrical member 52.

While I have shown and described a preferred embodiment of my invention, it is to be understood that I do not limit myself to the precise construction herein disclosed and the right is reserved to all changes and modifications coming within the scope of the invention as defined in the appended claims.

Having thus described my invention what I claim as new and desire to protect by United States Letters Patent is:

1. A device of the class described, comprising a window sash with sash support members slidably mounted in a window frame, a spring operated pulley rotatively mounted and arranged for aiding motion of the said sash support members, a cylindrical member eccentrically mounted for rotation, an arm extended from the cylindrical member, a counterweight adjustably mounted on the arm, and the said cylindrical member being arranged to press against the said pulley with forces as determined by the position of the said counterweight for partially nullifying the action of the spring operated pulley for providing smoother action.

2. In a device of the class described, a spring operated roller rotatively mounted and arranged for aiding motion of a sash member, a cylindrical member eccentrically mounted for rotation, an arm extended from the cylindrical member, a counterweight adjustably mounted on the arm, and the said cylindrical member being arranged to press against the said pulley with forces as determined by the position of the said counterweight for partially nullifying the action of the spring operated pulley for providing smoother action.

In testimony whereof I have affixed my signature.

RAFFAELE AVERSA.
